SLUG VALVE DRIVEN ICE MAKER

Donald E. Miller, Mount Prospect, and Carl C. Bauerlein, Lincolnwood, Ill., assignors to The Dole Valve Company, Morton Grove, Ill., a corporation of Illinois

Filed June 29, 1961, Ser. No. 120,631

4 Claims. (Cl. 62—137)

This invention relates to an ice making assembly of the type adapted to be installed in a household refrigerator and more particularly relates to a mechanism for controlling the operation of a distortable tray assembly wherein ice blocks are mechanically ejected from the tray by twisting the tray about its longitudinal axis. More specifically the invention is directed to an improved mechanism which will automatically energize a tray distorting means shortly after ice blocks have become completely frozen therein and which will control the liquid filling of the ice tray at proper intervals and in the proper volume but which is itself deenergizable when the ice blocks accumulated in the storage tray have reached a predetermined level.

A slug valve is employed for the purpose of dispensing a predetermined volume of liquid to the ice tray and this valve is of the usual type having a piston which is movable during filling and emptying of the valve. A gear rack is connected to this piston and is cooperable with a segmental driving gear mounted on a shaft journaled within a housing which, in turn, is drivably engageable with a shaft mounted driven gear connected to one end of the ice tray. In this manner, rotation of the driven gear will effect rotation of the ice tray. By limiting the degree of rotatable movement of the opposite end of the ice tray, the tray can be distorted, by a twisting action about its longitudinal axis, simply by arranging the gear drive to rotate the said one end of the tray through a greater rotational arc than is permitted the free end of the ice tray.

Slug valve filling and the discharge of liquid from the slug valve to the ice tray is controlled by means of a temperature sensitive power unit which is energized in accordance with the rate of freezing of ice blocks within the ice tray. Slug valve filling is also controlled as a function of the level of ice blocks within the storage tray so that the entire control assembly is completely automatic.

We have so devised this mechanism, however, that it requires only a single power source; namely the temperature sensitive power unit. It does not necessitate the provision of separate solenoids or electrical drive means and does not require any electrical connections. Furthermore, the entire mechanism is completely contained in a single unit, thereby obviating the assembly disadvantages of working with a plurality of subassemblies.

It is a principal object of the present invention to provide an improved automatically operable ice making assembly.

A more specific object of the invention resides in the provision of an automatically operable ice making assembly which requires no electrical connections and which requires only a single power source; namely the thermal mechanical transducer.

A still further object of the invention is to provide an entirely automatically operable ice making assembly which is completely self-contained within a single unit.

These and other objects of the invention will appear from time to time as the following specification proceeds and with reference to the accompanying drawings, wherein:

FIGURE 1 is a pictorial view of an ice making apparatus constructed in accordance with the principles of the present invention mounted within the freezing compartment of a household refrigerator;

2

FIGURE 2 is a plan view of the ice making apparatus of the present invention showing some parts in elevation and others in horizontal section;

FIGURE 3 is a vertical sectional view through the apparatus of our invention in a first position;

FIGURE 4 is a fragmental vertical sectional view through the apparatus which is similar in nature to FIGURE 3 but which illustrates various parts in different positions;

FIGURE 5 is a vertical sectional view similar to FIGURE 3 but showing the parts in yet another position;

FIGURE 6 is another vertical sectional view of various parts of the apparatus;

FIGURE 7 is a vertical sectional view taken along lines VII—VII of FIGURE 5;

FIGURE 8 is a vertical sectional view taken along lines VIII—VIII of FIGURE 5 with parts thereof shown in elevation;

FIGURE 9 is an end view of our apparatus showing some parts in vertical section; and

FIGURE 10 is a horizontal sectional view through the valve illustrated in FIGURE 9.

The tray twist mechanism

Referring initially to FIGURE 1, an ice tray 10 is disposed within a freezing compartment 11 of a normal household refrigerator and a collection tray 12 lies on the base wall 13 of the freezing compartment below the tray 10 to collect ice blocks which are ejected from the ice tray. A pair of shafts 15 and 16 are connected to opposite ends of the tray 10 and are journaled within a housing 20 and plate 18, respectively. The plate 18 has its base secured to the base wall 13 of the freezing compartment 11 and constitutes a support for the shaft 16 which is secured to what may be termed the "free end" of the ice tray. The housing 20 has a right angular flange 21 formed integrally therewith which is bolted to a closure plate 22 which, in turn, is rigidly secured to the side wall of the freezing compartment 11.

Stiffening arms 23 and 24 are connected to and corotatable with the shaft 15; the former overlying an end 25 of the ice tray and the latter lying along the lower surface of that end of the ice tray. Similarly, stiffening arms 26 and 27 are secured to the shaft 16 and lie along the lower and upper surfaces, respectively, of the free end 28 of the ice tray.

The tray 10 is preferably formed of high density polyethylene so that it may be flexed or twisted under low temperature conditions without breaking. High density polyethylene may have a very smooth and somewhat waxy surface so that a relatively weak bond is formed between the ice blocks which are formed within the molds in the ice tray and the walls of the individual ice molds. By turning the tray over and subsequently distorting the tray by applying a longitudinal twist thereto the ice blocks will be ejected from the tray and fall into the collection tray 11.

Longitudinal flexure of the tray is effected in the following manner: the shaft 15 is rotated to turn the tray over and rotation of the tray continues until the arm 27 comes into contact with a stop 30 which extends outwardly from the plate 18. Thereafter the free end 28 cannot move through a greater arc so that continued rotation of the shaft 15 in the same direction will twist the tray about its longitudinal axis. The stiffening arms 23, 24, 26, and 27 serve to rigidify the opposed ends of the tray so that torque will be most effectively transmitted to every part of the tray. Also, the walls of the individual molds within the tray are generally curvilinear so that an ice block will readily be dislodged from its respective mold when torque is thus applied to the tray.

The means for effecting the desired degree of rotation of the shaft 15 is sequentially illustrated in FIGURES 3, 4, and 5 in conjunction with FIGURE 2. The shaft 15 has one end journaled within the plate 17 and has its opposite end journaled within a bore 31 formed in a boss 32 which protrudes inwardly from a cover 33 which closes the casing 20 and which is secured to the casing by self-tapping screws.

A segmental circular driven gear 35 is corotatable with and affixed to the shaft 15 and is illustrated in FIGURE 10 with a shoulder 36 in engagement with a stop pin 37. The stop pin 37 has its opposite ends disposed within bores formed in the cover 33 and the face 17 of the casing 20. A torsion spring 38 encircles the shaft 15 and has an outturned arm disposed within the plate 17 and another arm lying on the ice tray 10 so that the spring 38 tends to bias the shaft in a direction to dispose the tray in a liquid receiving position.

A drive gear 40 has gear teeth formed through an arc of approximately 70° at diametrically opposed points thereon and is corotatably affixed to a shaft 41 which is journaled in the casing 20 and cover 33 as best viewed in FIGURE 8. The toothed segments of the gear 40 are engageable with the gear 35 to effect rotation of that gear in a counterclockwise direction as viewed in FIGURE 3. Of course, when the gear 40 has rotated to the position illustrated in FIGURE 3, its gear teeth will have moved out of engagement with the gear 35 and the torsion spring 38 will have rotated the shaft 15 and gear 35 to the position illustrated therein. Keyed to the shaft 41 is a ratchet gear 43 having four segmental spiral-form driving lugs 44 formed about the periphery thereof. The maximum radius of each spiral-form lug 44 terminates in a shoulder 45 extending substantially along a radius line extending through the center axis of the shaft 41.

A drive link 47 is freely mounted on the shaft 41 and has a plurality of gear teeth 48 formed around the circular base thereof. A pawl 50 is pivotally mounted on the outermost end of the link by a pin 51 and has a face 52 which is engageable with the shoulder 45 to rotate the ratchet 43 in a clockwise direction. A tension spring 53 interconnects the free end of the pawl 50 with the link 47 and serves to bias the pawl into engagement with the peripheral edge of the ratchet 43.

The slug valve

A piston 55 having a shaft 56 formed integrally therewith is mounted within a cup-shaped portion 57 of a block 58 with the shaft 56 mounted for sliding movement within a bore 59 in the block. The block 58 is mounted within the side wall of the freezing compartment 11 and is formed integrally with the plate 22.

A flexible diaphragm 60 is seated on top of the piston 55 and has a peripheral annular bead 61 disposed within an annular groove formed in the face of the block 58 adjacent the open end of the cup-shaped portion 57. A valve cover 62 overlies the periphery of the diaphragm 60 to maintain the diaphragm in its proper seated position and has a recessed interior of sufficient diameter to permit free travel of the piston 55 thereinto. The cover 62 is affixed to the block 58 by screws or the like. A compression spring 64 is mounted within the cup-shaped portion 57 with one end in engagement with the block 58 and its opposite end in engagement with the piston 55 so that the piston is biased to the position illustrated in FIGURE 3.

The piston 55 and cover 62 thus define a chamber 65 which may be rendered communicable with a source of pressurized water through a port 66 formed in the wall of the cover 62. The piston and associated structure here described comprise what is known in the art as a "slug valve." The force of pressurized water entering the chamber 65 through the port 66 will be sufficient to overcome the opposing biasing force of spring 64 and move the piston 55 from the position illustrated in FIGURE 3

to the position illustrated in FIGURE 5. Thereafter, by openly communicating the chamber 65 with an outlet, the spring 64 will urge the piston 55 to the right and water will be expelled from the chamber 65.

A gear rack 68 is formed integrally with the shaft 56 and is cooperable with the gear teeth formed about the base of the drive link 47 so that longitudinal movement of the piston shaft and gear rack will effect rotatable movement of the drive arm 47.

Assuming that the drive arm 47 is initially in a slightly more counterclockwise rotated position than is illustrated in FIGURE 3 and that the face 52 of the pawl 50 is in engagement with a shoulder 45 of the ratchet 43, the operation of the device will be as follows: the entrance of pressurized water into the chamber 65 will urge the piston from the right to the left and the longitudinal movement of the gear rack 68 will move the drive arm 47 in a clockwise direction and will act through the pawl 50 to effect clockwise rotation of the ratchet 43, gear 40, and shaft 41. Return movement of the piston 55 toward the right will rotate the drive arm 47 freely on the shaft 41 in a counterclockwise direction to reposition it for another identical cycle.

Since gear teeth are formed along the edge of the gear 40 through only approximately a 70° arc at each of the diametrically opposed points on the gear, and since the various parts of the mechanism are arranged as illustrated to effect rotation of the ratchet 43 through only a 90° arc during each piston power stroke, two power strokes of the piston will be necessary to move the lowermost illustrated gear teeth on the gear 40 into driving engagement with the gear 35. Thus, on the first power stroke of the piston 55 the gear 40 will be moved rotatably 90° out of the position illustrated in FIGURE 3 in a clockwise direction. On the next power stroke the lowermost illustrated peripheral gear teeth on the gear 40 will move into engagement with the gear 35 and will effect counterclockwise rotatable movement of the gear 35 and shaft 15. At the end of this second power stroke, the peripheral gear teeth on the gear 40 will move out of engagement with the gear 35 as illustrated in FIGURE 5 and will permit the torsion spring 38 to return the gear 35 and shaft 15 to the position illustrated therein.

The water flow control valves

Referring now especially to FIGURES 9 and 10, a three part valve body 70 has an inlet 71 communicable with a normal pressurized household water supply and is mounted on the cover 62 with a gasket 73 lying therebetween to provide a fluid-tight seal between the valve body and the cover.

The valve body 70 includes a central section 74 having three spaced bores 75, 76, and 77 formed therein which are respectively communicable with radially enlarged inlet and outlet chambers 78 and 79. Diagonal passages 80 and 81 communicate the outlet chambers of the bores 75 and 76 with the inlet chambers of the bores 76 and 77, respectively. The inlet 71 is communicable with the inlet chamber 78 of the bore 75. Valve rods 82 and 83 extend through the bores 75 and 76, respectively, and have flexible annular diaphragms 84 and 85 extending therefrom which have their edges seated in recesses formed around the outlet chambers 79 of the respective bores. A flexible annular diaphragm 86 is also mounted on a valve rod 87 extending through the bore 77 and the edge of this diaphragm is likewise seated on the valve block 74.

A closure cap 88 fits over the valve rods and slidably engages those rods and seats on the peripheral edges of the diaphragms 84, 85, and 86 to maintain these diaphragms in their proper positions. The cap 88 is affixed to the valve block 74 by means of a plurality of screws 89.

Diaphragms 90 and 91 are likewise affixed to the opposite ends of the rods 82 and 87, respectively, and these diaphragms are maintained in their proper mounted positions by a pillow block 92 which is also affixed to the

valve block 74 by the screws 89. A gasket 93 encircles the inlet port 78 of the bore 76 to provide a fluid-tight seal and is also maintained in position by the pillow block 92.

Valve members 94, 95, and 96 are affixed to the inner ends of the valve rods 82, 83, and 84, respectively, and are engageable with the annular shoulders defining the ports 75, 76, 77; the valve members 94 and 96 being shown as formed integrally with the diaphragms 90 and 91. Similarly, a valve member 97 is formed integrally with the diaphragm 86 and is cooperable with a shoulder defining the upper end of the bore 77 as viewed in FIGURE 10.

It will be understood that the diaphragms 84, 85, 86 may be formed of resilient material and be so configurated that they normally tend to bias the rods 82, 83, and 87 in a direction to seat the valve members 94, 95, and 96 on their respective shoulders.

An outlet passage 98 is communicable with the bore 77 and leads to an aperture 99 formed in the casing 62 which opens to the chamber 65.

Accordingly, if each of the valve rods is depressed, water may flow from the inlet 71 through the several bores and chambers to the outlet passage 98 and thence to the chamber 65. If any one of the valve members 94, 95, or 96 is seated on its respective shoulder, communication between the inlet 71 and the chamber 65 will be closed.

Turning now to FIGURES 6 and 9, a housing 100 has a storage chamber 101 formed therein which has an outlet 102 leading from a port 103 formed in the base thereof and terminating in a short lip 104 which protrudes from the plate 22. Fitted on the lip 104 is a resilient tongue 105 which delivers water from the passage 102 to the ice tray 10. A plurality of curvilinear grooves 106 are formed within the partitioning walls in the ice tray so that the water delivered to one of the molds from the tongue 105 will be distributed throughout the entire ice tray.

A cap 107 is seated on the housing 100 to close the storage chamber 101 and this cap has a nipple 108 threaded therein which serves as an inlet to the storage chamber 101. The nipple 108 is disposed in open communication with the outlet chamber 79 of the bore 77 through a hose 109 and a fitting 110 which opens to the outlet chamber 79 as viewed in broken lines in FIGURE 9.

It will thus be observed that when all of the valve rods 82, 83, and 87 are depressed, water may be communicated from the inlet 71 to the chamber 65 in the slug valve to move the piston 55 to the position illustrated in FIGURE 5. Upon movement of the valve rod 87 to the position illustrated in FIGURE 10, communication between the inlet 71 and the chamber 65 will be closed by the valve member 96 but the valve member 97 will be unseated and the spring 64 will act to move the piston 55 in a direction to decrease the volumetric capacity of the chamber 65 and water will be forced back through the port 66, bore 77, and hose 109 into the storage chamber 101.

Snap action valve control

Movement of each of the valve rods is effected in a different manner. The valve rod 87 is moved as a function of the position of the piston 55 in the manner hereinafter described. A supporting structure 112 comprising a pair of spaced uprights 113 and 114 and a pair of horizontal supports 115 is secured to the cover plate 33 by screws 116 extending through the cover plate and screw threaded into one of the horizontal supports 115. The horizontal supports 115 are each notched as at 117 on their upper and lower surfaces. Snap blades 118 and 119 are mounted above and below the horizontal supports 115 with their edges in the notches 117 and are interconnected by an overcenter spring 120 which is connected to each blade adjacent the free end thereof. A depending finger

121 depends from the blade 119 and is received within a slot 122 formed in the horizontally extending flange 123 of a bracket 124 which is affixed to the gear rack 68.

A valve rod 87 extends through a guide block 125 and 5 guide boss 126 and is slidably received by a channel groove formed in the upper end of the upright member 114. The innermost end of the guide rod 87 is radially reduced as at 127 and this radially reduced portion of the guide rod is received within a complementary U-shaped groove 129 formed in the upper end of the blade 118. A collar 130 is formed integrally with the valve rod 87 and is engageable with the upright 114 to prevent the valve rod 87 from moving further to the left than is illustrated in FIGURE 5.

15 It will then be observed that movement of the piston 55 from the position illustrated in FIGURE 5 toward the right will act to move the blade 119 past the plane of the blade 118 and the spring 120, having thus passed "over center," will snap the blade 118 from the position illustrated in FIGURE 5 to the position illustrated in FIGURE 3. Such movement of the blade 118 will act to move the valve rod 87 toward the right as viewed in FIGURE 5 or depress that rod to unseat the valve member 96 from its respective shoulder. Conversely, movement of the piston toward the position illustrated in FIGURE 5 will act through the blades 118 and 119 to move the valve rod 87 in an opposite direction to unseat the valve member 97 from its respective shoulder.

Ice level sensitive valve mechanism

30 As best viewed in FIGURES 2, 6 and 8, an ice level sensing arm 140 has an end 141 journaled for rotatable movement in the support 18 and has an elongated opposite end portion 142 similarly journaled for rotatable movement in the casing 20 and closure plate 33. The sensing arm is so formed that an ice level contacting portion 143 thereof is normally disposed in a raised position adjacent the ice tray out of the path of ice blocks ejected from the ice tray 10. This position is shown in broken lines in FIGURE 6.

35 Counterclockwise rotation of the sensing arm from the position illustrated in broken lines in FIGURE 6 to the position illustrated in full lines therein moves the ice contacting portion 143 thereof to a position within the upper portion of the collection tray 12. Resilient drive means are provided for moving the sensing arm from the full line position in FIGURE 6 to the broken line position therein so that when the level of ice blocks within the tray 12 has risen above the ice contacting portion 143 of the sensing arm, the sensing arm will be prevented from returning to the broken line position. By controlling the operation of the ice making apparatus in accordance with the position of this sensing arm, the apparatus can be operated as a function of the level of ice blocks within the collection tray 12. It will be understood, of course, that the sensing arm may be arranged to sweep over the top of the collection tray rather than through the upper portion thereof; the particular arrangement being merely a matter of preference.

40 As viewed in FIGURES 3 and 8, a tubular member 145 having an arm 146 formed integrally therewith and depending therefrom is keyed to the end portion 142 of the sensing arm 140. The arm 146 abuts the innermost end of a rod 148 which is mounted for sliding movement in the guide block 125 and guide boss 126. The outer end of the rod 148 abuts the plunger 83 so that movement of the rod 148 to the right in FIGURE 3 will depress the plunger 83 to unseat the valve member 95 from its respective shoulder.

45 A collar 149 is formed on the rod 148 and serves as a seat for one end of a compression spring 150 which has its opposite end seated on a plug 159 mounted within a radially enlarged bore 152, thus biasing the rod 148 to the left as viewed in FIGURE 3. When the rod 148 is in this left-hand-most position, the plunger 83 will be extended and the valve member 95 will be seated.

A lever 155 extends outwardly from the tube 145 and a tension spring 156 serves to interconnect the free end of this lever with a wall of the casing 20 to bias the tube 145 in a counterclockwise direction. It will be understood that the biasing force of the tension spring 156 exceeds that of the compression spring 150.

The pawl 50 is disposed in the same vertical plane as at least a portion of the arm 146 and has a cam 158 formed thereon which is arranged to contact the arm 146 to rotate that arm and the tube 145 in a clockwise direction.

In operation the device functions in the following manner. Upon movement of the piston 55 to the right as viewed in FIGURE 3 the cam 158 will contact the arm 146 and rotate the tube 145 in a clockwise direction. Such rotation of the tube and the arm 146 will permit the spring 150 to move the rod 143 to the left to allow the plunger 83 to move extensibly to seat the valve member 95. Such movement of the arm 146 will raise the sensing arm 140 to the position illustrated in broken lines in FIGURE 6. Further movement of the piston 55 toward the right will effect further counterclockwise rotation of the drive arm 47 and as soon as the leading edge of the pawl 50 passes the shoulder 45, the spring 53 will snap the pawl inwardly toward the center axis of the shaft 41 and the arm 146 will be released from the cam 158. If the level of ice within the collection tray 12 is sufficient to prevent return movement of the sensing arm, the arm will remain in its depending position and the valve member 95 will remain seated on its respective shoulder preventing the flow of water therepast. If no ice blocks are disposed in the path of return movement of the sensing arm, the tension spring 156 will rotate the tube 145 in a counterclockwise direction as soon as the arm 146 is released from the cam 158 and the control rod 83 will be depressed to unseat the valve member 95. Since filling of the ice tray is controlled by the valve 70 and since the flow of water through the valve 70 is prevented whenever any one of the valve members 94, 95, or 96 is closed, the filling of the ice tray is thus controlled as a function of the level of ice within the collection tray 12.

Temperature sensitive valve mechanism

A thermal sensitive power unit 160 having a power member 161, a piston guide 162, and a temperature sensitive portion 163, is mounted in the housing 100 with its temperature sensitive portion 163 disposed within the chamber 101. The power unit 160 is of a type which contains a water or water-alcohol mixture or the like within the temperature sensitive portion 163 thereof so that the expansion of this substance, effected upon decreases in ambient temperature to a predetermined critical point, will move the power member 161 extensibly from the guide 162. The outermost end of the power member 161 is cooperable with the plunger 82 so that the plunger 82 is depressed to unseat the valve member 94 from its respective seat when the power member 161 moves extensibly from the guide 162.

In order to effect cyclic operation of the power unit 160 in accordance with the rate of freezing of ice blocks within the ice tray 10, a plug 164 is threaded into the plate 22 and engages the temperature sensitive portion 163 to provide the desired amount of heat transfer from the air ambient to the ice tray 10 to the power unit 160.

A spring (not shown) is disposed within the power unit 160 which biases the power member 161 to a retracted position. The normal household temperature of water directed to the chamber 101 will be sufficient to raise the ambient temperature around the power unit above its critical point and this spring will be effective to retract the power member 161 to permit the plunger 82 to move to its extended position. Thus, by controlling heat transfer through the plug 164 so that the cycle of operation of the power unit 160 is slightly greater than

the time required for ice blocks within the tray 10 to freeze, the plunger 82 will be actuated approximately in accordance with the rate of freezing of those ice blocks.

A valve rod 166 is journalled for rotatable movement in side walls 167 and 168 of the housing 100 and has a finger 169 which abuts a collar 165 formed on the power member 161 so that linear movement of the power member will effect rotary movement of the rod 166. The rod 166 has an arm 170 extending therefrom which is pivotally secured to a plunger valve 171. The plunger valve 171 is cooperable with the port 103 to control the flow of water from the chamber 101 and is guided through its stroke by a guide 172 extending from a wall of the housing 100.

A latch 173 is mounted for pivotal movement on the guide block 125 and has an arm 174 which also engages the collar 165. A latch finger 175 is formed on the opposite end of the latch 173 and is cooperable with a collar 176 formed on the rod 87 to prevent movement of the rod 87 toward the right when the latch 173 is in a counterclockwise rotated position. A torsion spring 177 interconnects the latch 173 with the guide block 125 to normally bias the latch 173 in this counterclockwise rotated direction.

Operation of the ice making assembly

Assume that the water within the ice tray has just been frozen into ice blocks and that the various parts of the mechanism are in the position illustrated in FIGURE 3. The power member 161 is in its retracted position and the valve members 95 and 96 are both unseated from their respective shoulders while the valve 94 is in the position shown in FIGURE 10. Shortly after the water within the tray has been frozen into ice blocks the temperature transmitted to the temperature sensitive portion 163 of the power unit 160 will be lowered to a predetermined critical point and the consequent expansion of the water or water-alcohol mixture therein will effect extensible movement of the power member 161. The outermost end of the power member 161 will move into engagement with the plunger 82 and depress that plunger to unseat the valve member 94 from its respective seat.

At the same time the rod 166 will rotate to seat the plunger valve 171 in the port 103. Since each of the valve members 94, 95, and 96 is unseated from its respective shoulder, water will flow from the inlet 71 through the port 66 to the chamber 65 and move the piston 55 toward the left. Such piston movement will act to rotate the lever arm 47 so that the pawl 50 will rotate the gear 40 through a 90° arc. Such movement of the gear 40 will act through the gear 35 to effect rotation of the shaft 15 to twist the ice tray 10 in the manner heretofore described. Ice blocks will then be ejected into the collection tray 12. When the piston 55 has moved a sufficient distance to the left, the blades 118 and 119 will be snapped to an overcenter position by the spring 120 and the rod 87 will be moved to the left to seat the valve member 95 and unseat the valve member 97. Such movement of the rod 87 will shut off the inlet flow of water to the chamber 65 and will communicate the chamber 65 through passages 66, 77, 79, 110, 109, and 108 with the chamber 101. The compression spring 64 will then urge the piston 55 to the right to force water from the chamber 65 to the chamber 101.

The relatively high temperature of water entering the chamber 101 will raise the ambient temperature about the power unit 160 above the critical temperature of the substance contained therein and the spring within the power unit 160 will act to retractably move the power member 161. The casing 100 is disposed in the insulated side wall of the freezing compartment so the water within chamber 101 will not freeze. When the power member 161 has moved nearly to its retracted position, it will act through the rod 166 to raise the plunger valve 171 from the seat 103 and the water contained within the chamber

101 will flow through passage 102 to the ice tray 10. It is contemplated that the volume of water contained within the chamber 101 will be sufficient to only half fill the tray 10 so that another complete cycle will be effected before the tray is twisted to eject ice blocks therefrom. This feature has been provided so that the ice blocks within the tray can be frozen in layers thus decreasing the length of time necessary to freeze the ice blocks.

Of course, as the piston 55 moves toward the right to expel water from the chamber 65 the snap blade 119 will be moved to an overcenter position to urge the control rod 87 to the right once more. However, the power member 161 will move very slowly to a retracted position and as long as it is an extended or partially extended position, the latch 173 will be in a counterclockwise rotated position to prevent the rod 87 from moving toward the right. When the power member 161 has moved to a nearly fully retracted position, the collar 165 will engage the arm 174 and rotate the latch 173 to release the control rod 87 so that it can be moved to the right under the bias of overcenter spring 120. The arm 174 and finger 169 are configured so that the collar 165 will contact the finger 169 first to unseat the plunger valve 171 before the latch 173 is tripped. This assures that the storage chamber 101 will be emptied prior to the time when filling thereof is effected.

The next complete cycle of operation will be identical to that above described except that the tray 10 will not be twisted. No twisting will result since the gear 40 will simply be moved rotatably in a clockwise direction 90° from the position illustrated in FIGURE 5 and no gear teeth thereon will engage the gear 35 to effect rotation of that gear. Thus, another layer of water will be placed on the frozen ice blocks already within the ice tray and a complete cycle will again be repeated before ice block ejection is effected. Ice block ejection thus takes place only on every second stroke of the piston 55.

This embodiment of the invention has been used for illustrative purposes only and various modifications and variations in the invention may be effected without departing from the spirit and scope of the novel concepts thereof.

We claim as our invention:

1. An ice making assembly comprising a housing having spaced input and output shafts journaled therein, a flexible ice tray disposed within a freezing compartment and having one end mounted on said output shaft, stop means limiting the degree of rotatable movement of the opposite end of said ice tray, a chamber formed within said housing having a port and having a wall which is movable to vary the volumetric capacity of said chamber, means biasing said wall in a first direction to decrease the volumetric capacity of said chamber, valve means operable to communicate said port with a source of pressurized water to urge said wall in an opposite direction and to permit said biasing means to urge said wall in said first direction to discharge the water through said port, a storage chamber for containing water discharged from said port, passageway means directing water from said storage chamber to said ice tray, a member connected to and extending from said wall, a segmental driving gear mounted on and corotatable with said input shaft, a driven gear mounted on and corotatable with said output shaft and engaged with said driving gear, motion translation means for converting linear motion of said member to rotary motion of said driving gear, temperature sensitive power means positioned within said storage chamber having an element extensible therefrom upon predetermined critical temperature conditions and cooperable with said valve means to effect actuation thereof, and means for effecting heat transfer between said temperature sensitive power means and the air ambient to said ice tray and for correlating the interval required for said power means to reach said critical temperature conditions with the in-

terval required for water within said ice tray to be frozen into ice blocks.

2. An ice making assembly comprising a housing having spaced input and output shafts journaled therein, a flexible ice tray disposed within a freezing compartment and having one end mounted on said output shaft, stop means limiting the degree of rotatable movement of the opposite end of said ice tray, a chamber formed within said housing having a port and having a wall which is movable to vary the volumetric capacity of said chamber, means biasing said wall in a first direction to decrease the volumetric capacity of said chamber, valve means operable to communicate said port with a source of pressurized water to urge said wall in an opposite direction and to permit said biasing means to urge said wall in said first direction to discharge the water through said port, a storage chamber for collecting water discharged through said port, passageway means opening to said storage chamber for directing water discharged from said port to said ice tray, valve means cooperable with said passageway means to control the flow of water therethrough, a member connected to and extending from said wall, a segmental driving gear mounted on and corotatable with said input shaft, a driven gear mounted on and corotatable with said output shaft and engaged with said driving gear, motion translation means for converting linear motion of said member to rotary motion of said driving gear, temperature sensitive power means having an element which is extensible therefrom upon predetermined critical temperature conditions, motion translation means interconnecting said element with each of said valve means to effect actuation of said valve means, and means for effecting heat transfer between said power means and the air ambient to said ice tray and for correlating the interval required for said power means to reach said critical temperature conditions with the interval required for liquid within said ice tray to be frozen into ice blocks.

3. An ice making assembly comprising a housing having spaced input and output shafts journaled therein, a flexible ice tray disposed within a freezing compartment and having one end mounted on said output shaft, a storage tray positioned beneath said ice tray to collect ice blocks ejected therefrom, stop means limiting the degree of rotatable movement of the opposite end of said ice tray, a chamber formed within said housing having a port and having a wall which is movable to vary the volumetric capacity of said chamber, means biasing said wall in a first direction to decrease the volumetric capacity of said chamber, valve means operable to communicate said port with a source of pressurized water to urge said wall in an opposite direction and to subsequently permit said biasing means to urge said wall in said first direction to discharge liquid through said port, second valve means operable in series with said first-mentioned valve means to control the communication of said port with the source of pressurized water, means sensing the level of ice blocks within said storage tray and controlling the operation of said second valve means as a function of that level, passageway means directing water discharged from said port to said ice tray, a member connected to and extending from said wall, a segmental driving gear mounted on and corotatable with said input shaft, a driven gear mounted on and corotatable with said output shaft and engaged with said driving gear, motion translation means for converting linear motion of said member to rotary motion of said driving gear, and power means for controlling the operation of said valve means.

4. An ice making assembly comprising a housing having spaced input and output shafts journaled therein, a flexible ice tray disposed within a freezing compartment and having one end mounted on said output shaft, stop means limiting the degree of rotatable movement of the opposite end of said ice tray, a chamber formed within said housing having a port and having a wall which is

movable to vary the volumetric capacity of said chamber, means biasing said wall in a first direction to decrease the volumetric capacity of said chamber, valve means operable to communicate said port with a source of pressurized water to urge said wall in an opposite direction and to permit said biasing means to urge said wall in said first direction to discharge the liquid through said port, passageway means directing water discharged from said port to said ice tray, a gear rack connected to and extending from said wall, a segmental driving gear and a ratchet gear mounted for corotatable movement on said input shaft, a lever freely mounted on said input shaft having a pawl pivoted on the free end thereof which is engageable with said ratchet to effect rotatable movement thereof, a gear segment formed on said lever and cooperable with said gear rack so that linear movement of said

5

10

rack will effect rotatable movement of said lever, a driven gear mounted on and corotatable with said output shaft and engageable with said driving gear, and power means for controlling the operation of said valve means.
